UNITED STATES PATENT OFFICE.

OTTO PFÄNDER, OF BRUSSELS, BELGIUM.

AUTOMATICALLY-GOVERNED CARBURETER.

No. 920,642.

Specification of Letters Patent.

Patented May 4, 1909.

Application filed March 25, 1907. Serial No. 364,334.

To all whom it may concern:

Be it known that I, OTTO PFÄNDER, a subject of the German Emperor, residing at Brussels, in the Kingdom of Belgium, engineer, have invented certain new and useful Improvements in Automatically-Governed Carbureters, for which application has been made in France, August 8, 1906; Belgium, August 10, 1906; Germany, August 10, 1906, and Great Britain, August 11, 1906.

This invention relates to improvements in carbureters and is especially designed for use in connection with motor vehicles.

One of the objects of this invention is the provision of a carbureter equipped with means for controlling admission of the explosive fluid which means also serves to automatically effect admission of additional air and, in the preferred embodiment, a supplemental supply of air in order to obtain as nearly as possible a uniform richness of the explosive mixture when it is desired to change the speed of the engine and also when it is desired to quickly develop additional power in case of a sudden increase of speed.

The invention will be more fully described in connection with the accompanying drawing and will be more particularly pointed out and ascertained in and by the appended claims:

In the drawings:—The figure illustrates a longitudinal vertical section of a carbureter embodying the main features of my invention.

Like numerals of reference designate similar parts throughout the drawing. As shown 1 designates a casing in which is formed a guide channel 18. Said channel 18 communicates as shown with an annular receiving chamber 20 which delivers to a pipe or like connection communicating with the ignition chamber of the cylinder not shown and forms the outlet for the carbureter. As shown, means preferably in the form of a controller or a throttling plug 3 is provided and is slidably mounted in the guide channel 18. Said plug 3 is conveniently provided with means preferably in the form of slots 4 for progressively admitting the explosive mixture in increasing quantities to the chamber. The normal air supply is taken in at 6 and passes the nozzle 5 from which the explosive fluid is atomized or otherwise supplied from any suitable source such for instance as a tank 21. Inasmuch as the means for supplying the explosive fluid forms no

feature of the present invention it need not be described in detail. The plug 3 is provided with means for effecting the admission of an additional supply of air to the explosive mixture and as shown said means consists of apertures 7 which are normally closed by a flange 19 of the casing 1. Said plug 3 is also provided with means for effecting the admission or afflux of a supplemental supply of air to the explosive mixture and as shown said means consists of a valve closure 9 which is adapted to coöperate with a valve seat 22 formed in said plug 3. Apertures 8 formed in the plug 3 provide for the admission of air which is controlled by said valve. The closure 22 is conveniently provided with a stem 10 which projects outwardly through a guide 23 and which carries on its outer end an abutment or shoulder 24 between which and the guide 23 is interposed means in the form of a spring 11 serving to normally maintain said closure 9 upon its seat and prevent the admission of supplemental air. A shock reducer is provided to prevent hammering of the closure and as shown said reducer consists of a piston 12 mounted on the stem 10 and fitting the plug 3 closely. An outlet 13 affords a convenient escape for the cushion air when the piston 12 is returned by the spring 11 after the closure 9 has been opened. Means are provided for connecting the plug 3 with suitable operating mechanism such for instance as a governor, not shown, which means consists as shown of an arm 25 formed integral with the casing 1 and carrying on its outer end a pivotally mounted lever 15. Said lever 15 is suitably connected by means of a rod 17 with a governor or like actuating device and is also connected with a spring 16 which normally serves to hold the plug 3 in the position shown in Fig. 1. The lever 15 is slidably connected with the plug 3 by means which as shown consists of a stud 14 mounted on the guide 23 and adapted to engage a slot 26 formed in the lever 15.

The operation is as follows:—When the engine is operating at a relatively reduced speed the explosive mixture is admitted and the air supply is provided at 6, the mixture passing through slots 4 into chamber 20 and through outlet 2. It will be noted that when the plug 3 is in the position shown a relatively reduced quantity of the mixture is permitted to pass into the chamber 20. When however it is desired to increase the speed the plug 3 is moved in the direction of

the arrow a sufficient distance to open the ports 7 and effect admission of additional air which mingles with the explosive mixture. Such movement of the plug 3 gradually or 5 progressively increases the delivery to chamber 20 and this delivery is designed to govern the admission of both the explosive mixture and additional air by gradually opening the slots 4 to the chamber 20. In consequence of the resumption of speed due to the 10 admission of an increased quantity of the explosive mixture the pressure in the plug 3 is reduced sufficiently with respect to atmospheric pressure to unseat the closure 9 and admit a supplemental afflux of air through 15 ports or openings 8. Upon the return stroke of the piston the pressure in the plug 3 is restored and the spring 11 returns the closure 9 to its seat, the piston 12 serving to cushion 20 or retard the movement of the piston 12 and the closure 9 under the action of spring 11.

I claim:

1. A carbureter comprising in combination, a casing provided with an outlet, a 25 source of supply for the explosive mixture delivering to said casing, and a controlling member for limiting the flow of said mixture to said outlet, said controller being provided with means for automatically admitting additional air to said mixture, and said controller being also provided with means acting independently of said controller for automatically admitting supplemental air to said mixture.
2. A carbureter comprising in combination, a casing provided with an outlet, a 30 source of supply for the explosive mixture delivering to said casing, and a controlling member for limiting the flow of said mixture

to said outlet, said controller being provided with means for automatically admitting additional air to said mixture, and said controller being also provided with automatically acting means operated by internal pressure of said controller for admitting supplemental air to said mixture. 40 45

3. A carbureter comprising in combination, a casing provided with an outlet, a source of supply for the explosive mixture delivering to said casing, and a controller for limiting the flow of said mixture to said outlet, said controller being provided with openings or ports adapted to be closed by said casing for admitting additional air to said mixture, and said controller being also provided with an automatically acting valve controlled inlet for admitting supplemental air to said mixture. 50 55

4. A carbureter comprising in combination, a casing provided with an outlet, a 60 source of supply for the explosive mixture delivering to said casing, and a controller for limiting the flow of said mixture to said outlet, said controller being provided with openings or ports adapted to be closed by said 65 casing for admitting additional air to said mixture, and said controller being also provided with ports normally unobstructed for admitting supplemental air to said casing and an automatically acting valve for controlling the admission of said supplemental air through said ports to said casing. 70

In testimony whereof I affix my signature in presence of two witnesses.
